(57) **CLAIM**

The ornamental design for a long-handle tool holder as shown and described.

DESCRIPTION

FIG. 1 is a front perspective view of the claimed design, according to the first embodiment;

FIG. 2 is a top view of the claimed design of FIG. 1;

FIG. 3 is a front view of the claimed design of FIG. 1;

FIG. 4 is a bottom view of the claimed design of FIG. 1;

FIG. 5 is a front perspective view of the claimed design, according to the second embodiment;

FIG. 6 is a top view of the claimed design of FIG. 5;

FIG. 7 is a front view of the claimed design of FIG. 5; and,

FIG. 8 is a bottom view of the claimed design of FIG. 5.

1 Claim, 6 Drawing Sheets

FIG. 1

FIG. 2**FIG. 3**

FIG. 4

FIG. 5

FIG. 6**FIG. 7**

FIG. 8
